Inventor,

UNITED STATES PATENT OFFICE.

BURTON U. HILLS, OF CHICAGO, ILLINOIS.

AUTOMATIC FEEDING DEVICE FOR GRAPHITE OR THE LIKE.

1,384,892.

Specification of Letters Patent. Patented July 19, 1921.

Application filed April 1, 1918. Serial No. 225,951.

To all whom it may concern:

Be it known that I, BURTON U. HILLS, a citizen of the United States, residing at Chicago, in the county of Cook and State of Illinois, have invented certain new and useful Improvements in Automatic Feeding Devices for Graphite or the like, of which the following is a description.

My invention relates to means for feeding graphite, mica or other material in a finely divided or comminuted state to the cylinders of internal combustion engines or other bearing surfaces or places as desired.

The object of my invention is to provide a simple, reliable, convenient and serviceable device of the kind described whereby the finely flaked or powdered material may be fed continuously in any desired quantities and operating entirely automatically.

To this end my invention consists in the novel construction, arrangement and combination of parts herein shown and described and more particularly pointed out in the claims.

In the accompanying drawings wherein like or similar reference characters indicate like or corresponding parts.

Figure 1 is an elevation of an internal combustion engine showing my device attached to the intake manifold in operative position.

Fig. 2 is a vertical transverse section of my device.

Fig. 3 is a section taken substantially on line 3-3 of Fig. 2.

Fig. 4 is an enlarged sectional detail of the inlet nozzle and valve of my device taken substantially on line 4-4 of Fig. 2.

Fig. 5 is a view similar to Fig. 4 showing a slightly modified form of my device.

Fig. 6 is a view similar to Fig. 2 showing another slightly modified form of my device.

Fig. 7 is a view similar to Figs. 4 and 5 and showing another slight modification.

In the form shown my improved feeder comprises a receptacle 1 having a base 2 and a cap 3 and a transparent tubular body 4 positioned between the base and cap with gaskets 5 and 6 between the ends of the body part and the base and cap respectively. The base 2 is preferably a disk shaped member slightly concave on its upper side and provided with a laterally projecting marginal flange 7 at its upper edge adapted to overlap the gasket 5 and the lower end of the body part 4 slightly to maintain the parts

in position and form a suitable finish at this point.

A central tubular projection 8 is provided on the lower face of the base 2 having a part screw threaded as at 9 or otherwise formed, or provided with means for securing the receptacle in position when in service. The cap 3 is also preferably disk shaped and concave on its lower side with a marginal flange 10 substantially similar to the flange 7 of the base and adapted to serve substantially the same purpose.

The cap 3 is also provided with a central opening 11 extending therethrough and an annular face 12 surrounding the opening 11 adapted to coöperate with a nut 14 upon the upper end of a central stem 15 rigidly secured to the base 2 for rigidly maintaining the cap in position. The stem 15 is preferably tubular and screw-threaded at its lower end or otherwise provided with suitable means for rigidly securing the same to the base 2 while the upper end of the stem is provided with an internally threaded portion as at 16 adapted to coöperate with a screw 17 having a tapering part 18 at its lower end adapted to extend past the opening 19 through the wall of the stem slightly below the cap 3 to serve as a valve for controlling the flow of fluid from the receptacle into the stem. A convenient head 20 is provided at the upper end of the screw 17 and a jam nut 21 is mounted upon the screw adapted to coöperate with the upper end of the stem 1 to lock the screw in its adjusted position.

Any suitable means may be provided to admit air or other fluid to the interior of the receptacle 1. As shown a tubular head 22 is rigidly secured to the cap 3 extending transversely therethrough and a tubular part 23 is threaded or otherwise rigidly secured to the inner end of the member 22 with its lower end slightly above the inner face of the base 2. In the preferred construction the lower end of the tubular part 23 is flattened as shown in Figs. 2, 3 and 4 and curved slightly so that fluid entering the receptacle through the member will be directed at an angle toward the inner face of the base through a substantially radial slot thereby tending to create a current of air substantially parallel to the periphery of the receptacle. Suitable means are also provided to prevent the escape of air or fluid from the receptacle through the inlet open-

ing. For this purpose the head 22 is provided with a chamber 25 near its upper end and a valve 26 is positioned in the chamber having a part at its upper end adapted to 5 coöperate with the upper wall of the chamber to prevent the escape of air therethrough from the receptacle while permitting the air to freely pass therethrough into the receptacle. A spring 27 extends from 10 the upper end of the tubular part 23 to a part upon the valve 26 to normally maintain the valve in closed position. In the preferred construction also an orifice 28 is provided through the cap 3 and a plug 29 is 15 provided adapted to tightly fill the orifice so that graphite or other material may be conveniently introduced into the receptacle when desired. When thus constructed the receptacle 1 is preferably partially filled 20 with graphite or other finely divided material which it is desired to feed. The plug 29 is inserted and the receptacle is attached to the device to which the material in the receptacle is to be fed, for example, in the 25 form shown in Fig. 1 it is desired to feed graphite to the cylinders of an internal combustion motor and for this purpose my improved feeder is attached to the intake manifold of the motor near the carburetor.

30 When the motor is in operation the suction in the intake manifold is communicated to the interior of the receptacle and air enters the receptacle through the inlet 22-23 thus agitating the graphite in the receptacle and 35 causing it to pass with the air through the opening 19 into the tubular stem 15 and thence into the intake manifold where itmingles with and is carried by, the combustible mixture flowing through the manifold 40 into the several cylinders. The amount of graphite is controlled by adjusting the screw 17 and in order to avoid an accumulation of graphite on the walls of the passage leading to the manifold, a small orifice 30 45 may be provided through the wall of the projection 8 to permit a small amount of air to enter the passage at this point thus increasing the flow of air through the passage and sweeping any accumulation of graphite 50 adhering to the walls of the passage into the manifold. In the form shown in Fig. 5 my device is substantially constructed in all respects as hereinbefore described except that the member 31 corresponding to the head 55 22 in the form hereinbefore described is provided with an extension 32 at the exterior of the receptacle and a pipe 33 is attached thereto and connected to a suitable source of air or other fluid under pressure so that in 60 case it is desired to feed graphite or other finely divided material to a bearing or other space where there is no suction or where the suction is so slight as not to provide a satisfactory flow of fluid through the several 65 parts of my device the air or other fluid may

be supplied through the pipe 33 the fluid being forced into the receptacle and obviously operating in all respects substantially as hereinbefore described.

In the form shown in Fig. 6 the several 70 parts are shown substantially the same as in Fig. 5 except that the regulating screw 17 is entirely omitted and a nut 34 substantially corresponding with the nut 14 is formed to operate as a cap to close the upper end of 75 the stem 15. In this form a regulating valve 35 of any suitable form or construction is provided in the tube 36 leading to the fluid inlet of my receptacle so that the flow of fluid to the receptacle may be controlled 80 by the valve 35 as desired, thus obviously operating substantially as hereinbefore described. In the form shown in Fig. 7 the several parts are constructed and arranged substantially as shown in Fig. 6 except that 85 in this form a sleeve 38 is provided extending through the cap 3 and a tubular member 39 is rotatably mounted in the sleeve 38 with a curved tubular part 40 substantially 90 the same as the member 23 hereinbefore described attached to its lower end. A head 41 is provided at the upper end of the member 39 for rotating the inlet member 39 in the sleeve and a set-screw 42 or other suitable means is provided for locking the sleeve 95 in its adjusted position. In this form the regulation of the feed is accomplished by slightly rotating the inlet member and the part 40 so as to direct the entering air toward the periphery of the receptacle or 100 toward the center as it is desired to decrease or increase the feed, that is, if it is desired to decrease the feeding of material the member is so turned as to direct the current of fluid entering the receptacle toward the periphery of the receptacle where the centrifugal force of the eddying material in the receptacle will force the eddying particles of graphite or other material outward and prevent their escape through the opening 19. 110

To increase the feeding of material the member 40 is turned to direct the current of air toward the center of the receptacle thus decreasing the eddying action and permitting the particles to readily flow with the 115 air through the opening 19 in the stem 15.

Having thus described my improvement it is obvious that various immaterial modifications may be made in my device without departing from the spirit of my invention, 120 hence I do not wish to be understood as limiting myself to the exact form or construction shown.

What I claim as new and desire to secure by Letters Patent is:

1. A device of the kind described comprising a receptacle adapted to contain a comminuted material, means projecting into the receptacle for discharging the fluid therein at a point adjacent the bottom and toward 13

the periphery thereof, and means for directing a mixture of said material suspended in said fluid from said receptacle.

2. In a device of the kind described and in

5 combination, a fluid-tight receptacle adapted to contain a comminuted material, means provided with a nozzle at its lower end extending into the receptacle from near the periphery thereof, for directing fluid into 10 said receptacle near the bottom thereof and toward the periphery, and means for directing a mixture of said material suspended in said fluid from the upper part of said receptacle.

15 3. A device of the kind described comprising a receptacle adapted to contain a comminuted material, a tubular pipe projecting into the receptacle to adjacent the bottom thereof and provided with a substantially

20 flat nozzle for directing a fluid into the receptacle toward the periphery thereof and agitating the material, and means for directing a mixture of said material suspended in the fluid from the receptacle.

25 4. In a device of the kind described and in combination, a substantially fluid-tight receptacle having a tubular stem upon its base forming an outlet passage connected thereto near the upper end thereof, means projecting into the receptacle from near the periphery thereof to a point adjacent the bottom of the receptacle for admitting the fluid to said receptacle, and means operable from 30 the exterior of the receptacle for controlling the movement of the material passing through the said outlet passage.

35 5. In a device of the kind described and in combination, a substantially fluid-tight receptacle having an outlet passage connected 40 thereto on the interior near the upper end

thereof, and a tubular member provided with a nozzle at its lower end projecting into the receptacle below the normal levels of the contained material and means for controlling the directing of the movement of the fluid passing through said nozzle.

6. In a device of the kind described and in combination, a substantially fluid-tight receptacle having an outlet passage connected thereto near the upper end thereof, a tubular 50 pipe for admitting fluid to said receptacle, means operable from the exterior of the receptacle for controlling the movement of the material passing from the receptacle, and means in said pipe for automatically 55 preventing the re-admission of fluid to said receptacle through said outlet passage.

7. In a device of the kind described and in combination, a substantially fluid-tight receptacle having an outlet passage extending 60 through its base and connected to the receptacle on the interior thereof near the top, an inlet pipe having a nozzle at its lower end attached to the upper end of the receptacle near its periphery and projecting adjacent 65 the bottom of the receptacle for admitting fluid to the receptacle below the top of the contained material, means for controlling the movement of the fluid passing through the receptacle and means in said pipe for 70 preventing the re-admission of fluid to the receptacle through said outlet passage.

In testimony whereof, I have hereunto signed my name in the presence of two subscribing witnesses.
